CLAIM

(52) U.S. Cl. **D24/133**

The ornamental design for a portion of an interface for a medical instrument, as shown and described.

(58) Field of Search D24/133, 138; 600/101, 102, 117, 185; 606/139, 130; 128/4, 6; 901/2, 9

DESCRIPTION

(56) **References Cited**

This application is related to concurrently filed applications Ser. No. 29/097,552, filed Dec. 8, 1998, application Ser. No. 29/097,550, filed Dec. 8, 1998, application Ser. No. 29;097, 551, filed Dec. 8, 1998, the disclosures of which are herein incorporated by reference for all purposes.

U.S. PATENT DOCUMENTS

FIG. 1 is a bottom plan view of a portion of an interface for a medical instrument showing our new design; and, FIG. 2 is a top plan view thereof; at an enlarged scale. The broken line drawings of the environment in which the invention may be used forms no part of the claimed design. A perspective view, a front and rear a elevational view, and right and left elevation view are not shown since the claimed design does not appear in these views.
